UNITED STATES PATENT OFFICE.

MAX FISCHMAN, OF STREETSVILLE, ONTARIO, CANADA, ASSIGNOR OF ONE-THIRD TO ALEXANDER NELSON BURNS AND ONE-THIRD TO GEORGE HERBERT SMITH, BOTH OF TORONTO, CANADA.

FILLED MATTRESS.

No. 912,456.

Specification of Letters Patent.

Patented Feb. 16, 1909.

Application filed July 13, 1908. Serial No. 443,370.

To all whom it may concern:

Be it known that I, MAX FISCHMAN, of the village of Streetsville, in the county of Peel, in the Province of Ontario, Canada, have invented certain new and useful Improvements in Filled Mattresses, of which the following is the specification.

My invention relates to improvements in filled mattresses and bolsters therefor, and the object of the invention is to devise a strong, durable light mattress capable of maintaining its shape when in use, which will have a maximum resiliency and yet be soft to lie upon.

15 A further object is to make the mattress cheap.

A still further object is to make it in one form readily portable and capable of being rolled up in compact form for shipment.

20 To effect these objects I have constructed my mattress of a series of longitudinal rolls of raw cotton webbing, felt or batting or other suitable fibrous material wound layer like and having a central space in which is

25 located a series of vertically disposed springs located in an envelop and abutting each other, the said rolls extending across the mattress and abutting each other and being inclosed and held together by a suitable tick covering and a supplemental covering suitably held on to the mattress and provided at one end with a bolster, the parts being arranged and constructed in detail as herein-after more particularly explained.

30 Figure 1, is a perspective view of a mattress constructed in accordance with my invention, portion of the outer covering being broken away. Fig. 2, is a perspective view of portion of a mattress showing it partially broken away and in section. Fig. 3, is a longitudinal section through portion of the mattress. Fig. 4 is a longitudinal section of a portion of a mattress showing a modification. Fig. 5, is a cross section on the line 35 *x—y* Fig. 4.

In the drawings like characters of reference indicate corresponding parts in each figure.

40 Are a series of rolls formed of raw cotton webbing, felt or batting, which when they are first made are rolled layer-like in circular form around a divided metal cylinder. This cylinder encircles a longitudinal fabric envelop B made of a series of sections con-

taining spiral springs B' under pressure, that 55 is to say with the springs compressed. The envelop is divided lengthwise into a series of sections by rows 2 of stitching to incase the springs and hold them close together. The divided cylinder is withdrawn leaving the 60 springs B' in the envelop free to expand outwardly, which forces the previously formed circular roll into substantially rectangular form in cross section. The longitudinal sections of the envelop B, of course, are still partially under pressure, so that the form is 65 maintained.

The sections of the envelop B abut each other and extend from end to end of the roll, so that a uniform resiliency is imparted to 70 each roll. The rolls A extend across the mattress and abut each other, so that a soft top and bottom is given to the mattress making it reversible. These rolls are inserted in a tick 4 side by side and extend from end to 75 end thereof, the tick being afterwards closed at the end. The spring might be inserted under pressure in the rolls of raw cotton in another manner besides that of the longitudinally divided cylinder extending through 80 the roll.

C is a supplemental covering, which is buttoned by buttons C' down to the side of the mattress. The head end of the covering C extends around at C² to form the outside of a 85 bolster. The inside of the bolster is formed by a roll of raw cotton webbing D or the like wound layer on layer around centrally crossed spiral springs E and F, which are connected together by the cords F' and are provided with a suitable covering F² around 90 which the raw cotton or webbing or other suitable fibrous material is wound. The springs E and F are slightly under compression and thereby a comfortable bolster with 95 a very soft outer cushion of cotton, felt or batting is provided.

In the small spaces between the corners of each roll A', I provide a filling A², so as to make the top of the mattress smooth.

100 In Fig. 4, I show a modification particularly adaptable for a portable mattress. In this case I preferably make the spiral springs B² in distended form and abutting each other and wound around by the roll A³ of cotton 105 felt webbing or batting layerlike, the envelop being divided into sections by rows of stitching 3 so as to separate each spring. I pro-

vide a top and bottom covering 4' and 4², which are connected together by suitable rows of stitching between the rolls and connecting the rolls A³ together. A supplemental covering G formed of top and bottom layers of ticking G' and G² with intermediate filling G³ is provided, so that a smooth top surface for the mattress is provided. In this case the mattress is not reversible, but 10 is adapted to be a portable one and rolled with the cover G to the inside in roll-like circular form.

Such a mattress as I describe can be made very cheaply, has a maximum resiliency and 15 softness and is perfectly sanitary.

Although I describe the rolls as extending crosswise of the mattress it will, of course, be understood that they may with equal facility extend lengthwise.

20 What I claim as my invention is:

1. A mattress comprising a series of cushions placed side by side, each cushion comprising a row of springs, a series of pockets made from a suitable fabric, each pocket 25 inclosing a spring, a roll of fibrous material

wound in layer-like form around said pockets and a covering surrounding said cushions.

2. A mattress comprising a series of cushions placed side by side, each cushion comprising a series of coil springs, a cloth pocket 30 inclosing each of said springs, a roll of fibrous material wound in layer-like form around said pocket, a covering surrounding said cushions, and fibrous material located between the cover and the junction point of 35 two of the cushions.

3. A mattress comprising a series of cushions placed side by side, coil springs in the interior of said cushions, a cover surrounding the cushions and a bolster secured to the 40 cover, said bolster comprising a pair of coil springs arranged at right angles to each other, a cover surrounding said springs, a roll of fibrous material surrounding said cover, and an outer cover surrounding said roll.

MAX FISCHMAN.
